UNITED STATES PATENT OFFICE.

GEORGE E. HAMILTON, OF HARPER, OHIO.

FENCE-POST.

SPECIFICATION forming part of Letters Patent No. 394,266, dated December 11, 1888.

Application filed June 23, 1887. Serial No. 242,313. (No model.)

To all whom it may concern:

Be it known that I, GEORGE E. HAMILTON, a citizen of the United States, and a resident of near Harper, in the county of Logan and State 5 of Ohio, have invented a new and useful Fence and Fence-Post, of which the following is a specification.

My invention is an improved fence-post.

Figure 1 is a perspective view of my post 10 used with a picket fence; Fig. 2, a perspective view of my post used with a rail fence; Fig. 3, a perspective view of my post used with a board and wire fence; Fig. 4, a detached front view of the top of my post; Fig. 5, a perspective view of the bracket used to hold up 15 the stringers of a picket fence.

A is my post; B, a wing or piece projecting at right angles to the face of the corner-post, with a slot between the face of the post 20 and the wing; C, the slot in the post for the insertion of the rails or stringers of a fence; D, a bracket that fits in slot C and straddles the post; E, wings or flanges on the sides of the lower end of the post; F, a plate or 25 anchor on the bottom to prevent the frost from heaving the post; G, the stringers of a picket fence; H, fence-rails; I, boards of a fence; K, nails; Q, wire loops; P, staples; M, holes in the post through which the nails or 30 wires pass.

The object of my invention is to form a cheap, simple, iron fence-post that can be used in ordinary board, picket, or rail fences, and one, also, that is steadied from leaning 35 sidewise and anchored against being raised by frost.

To provide such a post, I cast it of the shape shown, the upper part being a flat loop, the sides of which have holes through them 40 for the passage of nails, wires, or staples. The loop also forms a slot, C, for the insertion of the stringers of a picket fence, or of the ends of rails when the post is turned crosswise. The bottom of the post below the loop has 45 projecting flanges in the form of a cross to steady the same in the ground, and also has a flat plate at the bottom to anchor the post and prevent its being raised by the action of frost.

When used as a corner-post, my post has a 50 wing or additional loop extending out at right angles to the face of the post, for the insertion of the ends of the boards, rails, or stringers of the portion of the fence running at right angles.

In using my post with an ordinary board or wire fence the post is turned, so that the boards fit against the flat side of the loop, as shown in Fig. 3, when ordinary nails are driven through the boards and through the 60 holes in the post and clinched on the opposite side of the post, or wires are passed over or through the boards and through the holes in the post and secured on the opposite side. Barbed or plain wire may be fastened on with 65 staples driven through the holes, or the wires themselves may be passed through the holes in the post.

In using my post with a picket fence the loops are turned crosswise of the line of the 70 fence, the brackets D are inserted in the loops at the proper height, as shown in Fig. 1, and nails are driven through holes in the bracket and loop and clinched. The stringers are then placed upon these brackets and the pickets nailed on.

The additional wing or loop on the corner-post presents a surface to nail boards to, and also forms a slot for the insertion of the fence-stringers in building a picket fence. 80

My bracket D, made in one piece, is a bracket, brace, and clamp combined, and is made as wide as the full width of my line-post, and has cut in each side a notch or groove the width and thickness of each wing 85 of the post. In use it is put edgewise in between the wings and then turned till its flat side is in a horizontal position, when the central solid part forms a brace to keep the wings from springing together, and the sides of the 90 grooves filling close to the sides of the wings of the post keep them from leaning or springing sidewise.

What I claim is—

1. A one-piece cast-iron fence-post, the upper part composed of three wings, the third wing being set at right angles to the other two and slotted at the point where the wings

would otherwise meet, so as to make an opening adapted to receive the ends of rails running at right angles to each other, as and for the purpose set forth.

5 2. A fence-post whose upper part is a loop having the eyes M therein, in combination with the one-piece bracket, brace, and clamp

D, having grooves or notches in its sides and attached to the post by pins or staples, as and for the purpose set forth.

GEORGE E. HAMILTON.
